UNITED STATES PATENT OFFICE.

SAMUEL B. GOLD, OF INDEPENDENCE, MISSOURI, ASSIGNOR TO WEBER ENGINE COMPANY, OF KANSAS CITY, MISSOURI, A CORPORATION OF IOWA.

MUFFLING-BREATHER-VALVE ATTACHMENT.

1,411,693.

Specification of Letters Patent. Patented Apr. 4, 1922.

Application filed June 16, 1919. Serial No. 304,604.

To all whom it may concern:

Be it known that I, SAMUEL B. GOLD, a citizen of the United States, residing at Independence, in the county of Jackson and State of Missouri, have invented certain new and useful Improvements in Muffling-Breather-Valve Attachments, of which the following is a specification.

This invention relates to muffling breather valve attachments for internal combustion engines, and my object is to produce a construction which provides for the intake of an ample volume of air in a relatively quiet or noiseless manner. A further object is to produce a construction of this character of simple, strong, durable and cheap construction.

To these ends the invention consists in certain novel and peculiar features of construction and combinations of parts as hereinafter described and claimed; and in order that it may be fully understood reference is to be had to the accompanying drawing, in which:

25 Figure 1, is an inner face view of a muffling breather valve attachment embodying the invention.

Figure 2, is a horizontal section of the same as applied to an internal combustion engine.

30 In the said drawing, 1 indicates the engine recessed circularly as at 2, and 3 indicates a head to fit against the end of the engine and in said recess, the rear edge of the head being provided with a plurality of opposing lugs 4.

Bolts 5 extend through the head, to secure the same rigidly to the end of the engine, and said head is provided with a plurality of large openings 6, bridged at their outer sides by cross pieces 7 cast integral with the heads.

Valve stems 8 extend slidably through the cross pieces 7 and the openings 6, and are equipped at their inner ends with flat valves 9 to cover their respective openings 6 and bear against the inner side or face of the head 3.

Coiled springs 10 fit loosely around the stems 8 and bear at their inner ends against the cross pieces 7 and at their outer ends against washers 11 fitting and secured on the stems 8 by nuts 12, the nuts being em-

ployed to facilitate the tensioning adjustments of the springs.

In the operation of the engine the proper action of the piston will tend to create a vacuum for unseating said valve and charging the engine cylinders with air to mix with gas therein and form a combustible mixture, the valve instantly reseating as the piston movement ends, under the reaction of the springs 10.

To muffle the intake action a substantially hemi-spherical cap 13 is fitted against the lugs 4 of the head 3, the cap preferably having corresponding lugs 14 to fit against said lugs 4 and cooperate with the same in providing a narrow air inlet 15, the cap being secured in place by cap bolts 16 extending through the said lugs and into the body portion of the engine.

I claim:

1. In an internal combustion engine, the combination with a crank case open at its rear end, of an annular head secured to the crank case over said opening and provided with a plurality of air intake openings, valves covering said openings at the inner side of the head, yielding means for holding the valves normally closed against the entrance of air into the crank case, and a cap secured to said head at the outer side thereof; said head and cap being spaced apart to provide passages for the entrance of air to the cap.

2. In an internal combustion engine, the combination of a crank case open at its rear end, a perforated head covering the rear end of the crank case and provided at its rear side with a marginal flange having a plurality of rearwardly projecting lugs, yielding-closed valves for said perforations and adapted for opening only to admit air to the crank case, and a hemi-spherical cap at the rear side of said head, and provided with forwardly projecting lugs engaging the lugs of said head and cooperating with the latter in spacing the head and cap apart between said lugs.

3. In an internal combustion engine having a crank case open at its rear end, a perforated head fitting against the rear end of the crank case around said opening and provided at its outer side with bridge bars

across its perforations, disk valves fitting bridge bars and at their outer ends against said nuts, and a hemi-spherical cap fitting at points against the outer side of said head and spaced from the latter between said bridge bars, nuts upon the outer ends of said stems, coiled springs around said stems and bearing at its inner ends against the

In testimony whereof I affix my signature.

SAMUEL B. GOLD.
